CLAIM

The ornamental design for an automobile, toy replica and/or other replicas, as shown and described.

DESCRIPTION

FIG. 1 is a front and left side perspective view of an automobile, toy replica and/or other replicas showing my new design, the front and right side perspective view being a mirror image thereof;

FIG. 2 is a front elevational view thereof;

FIG. 3 is a left side elevational view thereof, the right side elevational being a mirror image thereof;

FIG. 4 is a top and front perspective view thereof;

FIG. 5 is a top and rear perspective view thereof;

FIG. 6 is front elevational view thereof with the doors in open position; and,

FIG. 7 is another top and front perspective view thereof with the doors in open position.

The broken lines shown throughout the drawing are for illustrative purposes only and form no part of the claimed design.

1 Claim, 7 Drawing Sheets
